(57) **CLAIM**

The ornamental design for a dental mouthpiece, as shown and described.

DESCRIPTION

FIG. 1 is a Top Front Perspective view of a dental mouthpiece showing the new design;

FIG. 2 is a Front Elevation view thereof, with a Rear Elevation view being a mirror image thereof;

FIG. 3 is a Top Plan view thereof;

FIG. 4 is a Bottom Plan view thereof;

FIG. 5 is a Right Elevation view thereof; and,

FIG. 6 is a Left Elevation view thereof.

The broken lines shown in the drawings depict environmental structure that forms no part of the claimed design. The dot-dash broken lines depict the boundary of the claim and form no part of the claimed design.
